UNITED STATES PATENT OFFICE.

HARRY D. POMEROY, HAROLD T. AVERY, AND RAY M. WHEELER, OF SYRACUSE, NEW YORK.

DISK-RECORD CABINET.

1,360,680.

Specification of Letters Patent. Patented Nov. 30, 1920.

Application filed April 24, 1920. Serial No. 376,333.

To all whom it may concern:

Be it known that we, HARRY D. POMEROY, HAROLD T. AVERY, and RAY M. WHEELER, citizens of the United States, residing at 5 Syracuse, in the county of Onondaga and State of New York, have invented certain new and useful Improvements in Disk-Record Cabinets, of which the following is a specification.

10 Our invention relates to disk record cabinets, and particularly to cabinets of the class employed for selectively storing phonograph records and the like.

The object of our invention is to provide 15 a novel and simple record supporting means, which includes a novel structure for spacing and separating the disks. A further object is to provide a plurality of similar novel ejecting mechanisms, whereby any record 20 of a series may be readily and accurately selected, and then quickly expelled from the cabinet, the said mechanisms remaining in the operated positions while the records are being played, thereby indicating the vacant 25 compartment to which the records are to be returned. And a further object is to provide means for facilitating the selection of the records.

The various features and parts of the 30 invention will be understood from the detailed description which follows, and by reference to the accompanying drawing, in which—

Figure 1 is a broken front face view of the cabinet; the records being omitted. Fig. 2 35 is a vertical longitudinal section, taken on line 2—2 of Fig. 1; showing by full and dotted lines the various positions of the ejecting mechanisms. And Fig. 3 is a vertical cross-section, taken on line 3—3 of Fig. 40 2; showing the alternate and reverse arrangement of the ejecting levers.

In the drawing, 2 represents generally the hollow body of the cabinet, comprising the top 2', the lateral walls 2", the bottom 2", and 45 top and bottom front facings 2" and 2". The disk records 3 and 3' are of different diameters, as shown by dotted lines in Fig. 2, and these are supported by gravity upon a rigid laminated platform 4, which is preferably composed of alternating strips of wood 4' and thinner as well as broader strips of sheet fiber 4". The platform 4 is disposed horizontally parallel to the bottom 2", from which it is suitably spaced. The platform 50 preferably extends from one side wall 2" to

the other, and the top edges of the members 4' are preferably disposed on a level with the top edge of the facing 2". The members of the platform are all pierced by common supporting rods 4", the opposite ends of which may be anchored in the lateral walls 2". The top edges of the thin strips 4" preferably extend above the tops of the strips 4', thereby providing shallow parallel grooves or runways 4" for the record disks, 60 and each runway being wide enough to loosely receive a single disk. Above the platform 4, the cabinet is divided into a large number of narrow vertical compartments corresponding in breadth and position to the several runways 4" by a series of similar angular guards or spacers 5, having the same thickness as the strips 4", and whose reduced forward ends are also inserted between the wooden strips 4' in line 70 with the strips 4", and these ends are also pierced and held rigidly by one of the rods 4". The enlarged rear ends of the spacers 5 are rigidly secured to a transverse support 6 mounted on the rear wall 2", by common rods 6", as shown in Fig. 2. The record disks 3 and 3' are expelled from the cabinet 80 by means of reversely disposed individual ejecting levers 7 and 8, which are pivoted on transverse rods 7" and 8", the said rods being located respectively near the top and near the bottom of the cabinet. Both of said rods preferably have their opposite ends anchored in the side walls 2". The levers 7 and 8 are preferably arranged alternately, as best seen in Figs. 1 and 3, and their free ends overlap each other, as shown in all of the views. The levers 7 and 8 are normally held in true vertical position by the partitions 5, but in order to prevent their outer ends from shifting on the rods 7" and 8", similar spacing sleeves 7" and 8" are mounted on said rods. The outer ends of the levers 7 and 8 are broader than their free inner ends for increasing their strength. 90 The levers 7 and 8 are operated, *i. e.* swung on their respective pivots 7" and 8" for ejecting the records, by individual push-rods 7" and 8", the said rods piercing respectively the top and bottom facing plates 2" and 2". 100 The inner ends of the several push-rods are formed into hooks 7" and 8", which engage perforations or sockets in the thickened ends of the levers 7 and 8. The outer ends of the push-rods of the two series are staggered, 110

and are fitted with circular buttons or heads 7^a and 8^a which are engaged by the thumbs or fingers of the operators during the expelling of the records. Each of said buttons bears a different numeral, which corresponds to the number of a certain record, and each push-button is disposed in line with and serves to index a record compartment of the cabinet. In order to facilitate the selections of the records stored in our cabinet, the push-buttons 7^a contain only the even numbers, as 2, 4, 6 &c., all of which are disposed at the top of the cabinet, while the push-buttons 8^a contain only the odd numbers, as 1, 3, 5 &c., which are disposed along the bottom of the cabinet. When the operator desires a certain record disk, he consults the usual index for ascertaining the number of the record. He then finds the push-button bearing the said number, and pushes inwardly on said button. The inward movement of the push-button rocks the short end of the corresponding ejecting lever rearwardly, which tilts the free end of said lever forwardly for expelling the record (see dotted lines in Fig. 2). When the push-rods and ejecting levers are in their normally idle position, as shown by the full lines in Fig. 2, the said levers are all positioned vertically and bear against the support 6. When the record disks are placed in the cabinet, they are rolled rearwardly over and just beyond a stop consisting of a common rod 9, which passes through the spacers 4^a of the platform. The stop 9 prevents the accidental dislodgement of the records. This rearward movement of the disks forces any of the levers 7 or 8 which happen to be extended, as shown by the

dotted lines in Fig. 2 back against the support 6, where all of the parts remain until the keys 7^a and 8^a are operated, as described. After the operator has selected and expelled a record, he temporarily leaves the push-rod in the operated position for indicating the vacant compartment when the time comes for replacing the missing record. He is aided in this by the fact that the corresponding button is still in the depressed position, as he left it when the selection of the record was made.

Having thus described our invention, what we claim, is—

A cabinet for filing disk records, comprising a hollow body open at one end, a platform disposed horizontally in the body having upwardly facing grooves to receive and support record disks, inclined spacers for separating the records, ejecting levers separated and guided by said spacers, said levers arranged in series, the levers of one series alternating the levers of the other series throughout the body, one series of levers pivoted near the top of the body, the other series pivoted near the bottom of the body, the free ends of all of said levers overlapping near the horizontal axis of the body, a series of push-rods for operating the depending levers disposed across the top of the open end of the body, and a series of similar push-rods disposed across the bottom of the body for operating the series of inverted levers.

In testimony whereof we affix our signatures.

HARRY D. POMEROY.
HAROLD T. AVERY.
RAY M. WHEELER.
